UNITED STATES PATENT OFFICE.

JOHN KILBURN, OF BELMONT, MASSACHUSETTS.

SPINDLE-BEARING.

SPECIFICATION forming part of Letters Patent No. 590,822, dated September 21, 1897.

Application filed December 2, 1896. Serial No. 614,259. (No model.)

To all whom it may concern:

Be it known that I, JOHN KILBURN, a citizen of the United States, residing at Belmont, in the county of Middlesex and State of Massachusetts, have invented certain new and useful Improvements in Spindle-Bearings; and I do hereby declare the following to be a full, clear, and exact description of the invention, such as will enable others skilled in the art to 10 which it appertains to make and use the same.

The present invention relates to spindles, and more particularly to bearings for those spindles which are adapted when rotating under an unbalanced load to center themselves 15 and find their true center of rotation, and are generally designated as "top" spindles. As commonly constructed these spindles comprise a bolster having a tapered bearing and the blade or spindle, which has a tapered 20 end or pintle which fits into the tapered bearing of the bolster, the spindle-pintle resting at its end upon a "step" which supports it in such position relative to the bolster that it will fit the bearing in the bolster in a proper 25 manner to insure the easy rotation of the spindle in the bolster without undue friction. It has been found in practice that the rapid rotation of the spindle causes it to wear away at the end of the pintle or to wear away the 30 step, and that when so worn the tapered end of the pintle will fall into the tapered bearing of the bolster and will bind therein, causing an increase of friction between the spindle-pintle and bolster and requiring more power 35 to rotate the spindle and increasing the wear upon the parts.

To obviate the difficulties above noted, it has heretofore been proposed in the art to provide a vertically-adjustable step, whereby the wear 40 of the parts can be taken up and the spindle held in the proper position in its bearings.

The object of the present invention is to provide improved means for securing the vertical adjustment of the step and bolster and retaining them in their adjusted position after 45 said adjustment has been accomplished, and to the above end the present invention consists of the devices and combination of devices hereinafter described and claimed.

50 A preferred form of the present invention is shown in the accompanying drawings, in which similar letters of reference represent

similar parts throughout both views, and in which—

Figure 1 represents a vertical section 55 through the spindle-support, the spindle and other parts being shown in elevation. Fig. 2 represents a similar view showing the invention applied to a spindle-support comprising a suspended bolster. 60

In the drawings, A represents the spindle, having the usual tapered end or pintle a and carrying the sleeve-whirl B. C represents the bolster, D the bolster-case, and E the spindle-rail, all of which parts, except as hereinafter specified, may be of any usual or preferred form and arrangement. 65

In the form of my invention shown in Fig. 1 the bolster C is provided with a bearing c in its base to receive the step f, which is carried by the upper end of a pintle F and upon which the end of the spindle-pintle a is supported. 70

The bolster in the form of the present invention shown in Fig. 1 is supported at its 75 base preferably by means of pins d, driven into the bolster-case D to form a rest or support for the bolster C.

As before stated, the step f is arranged to be moved vertically by the rotation of the 80 bolster C, and it may be conveniently formed upon the top of said pintle, being arranged within a bearing d' in the bottom of the bolster-case, the end of the pintle and the bearing being of such construction that the pintle 85 may be moved vertically by a rotation of the bolster. Any suitable construction of the pintle F and the bearing d' may be provided which will enable the pintle F to be moved vertically without removing the parts from 90 the bolster-case D, and such adjustment of the pintle F and the step f, carried thereby, may be conveniently secured by providing the pintle F with a threaded end f' and by correspondingly threading the bearing d' in 95 the base of the bolster-case D.

The above-suggested arrangement is such that the step f may be adjusted to accommodate for the wear of the parts by the turning of the threaded end f' of the pintle F in its 100 bearing d' in the bolster-case D, thereby moving the step f vertically in the bearing c in the bolster C. It is designed that the pintle F shall be turned to adjust the step f by the

turning of the bolster C, and for this purpose the step f and bolster C are arranged to permit a free movement of the step within the bolster and to secure a rotation of the step 5 with the bolster, and this may be conveniently accomplished by forming the step portion f of the pintle F square or polygonal in cross-section or any suitable shape other than round and forming the aperture or bearing c in the 10 bolster of a corresponding shape, and as thus constructed when the bolster is turned it will turn the pintle F and by means of the threaded connection between said pintle and the bolster-case cause the pintle to move vertically, and thus move the step f vertically in 15 its bearing in the bolster C.

It is designed that the bolster be restrained from rotation and retained in a fixed position to thus maintain the adjustment of the pin 20 tole F, which has been produced by the rotation of the bolster, and, as shown in the drawings, this is effectively accomplished by forming a series of teeth c' upon the bottom of the bolster C or upon a ring or washer connected 25 therewith, the teeth being preferably formed with a substantially perpendicular face c³ and an inclined face c⁴. When thus formed, the faces c³ of teeth c', engaging with the supporting-pins d, restrain the bolster from rotation with the spindle, but permit it to be 30 rotated in an opposite direction to secure the adjustment of the pintle F, as before stated. Should it be desired, however, to restrain the bolster C from rotation by means other than 35 that shown, the teeth c' could be omitted and the bottom of the bolster left plain and unbroken and supported by the pins d, as before described.

As shown in Fig. 1, the parts are arranged 40 for a rotation of the spindle in a direction indicated by the arrow, Fig. 1, and the bolster to be turned in the opposite direction to raise the step f, but it is obvious that the construction could be arranged for a reverse movement of the spindle and bolster, if desired.

The operation of the invention as above described is as follows: The parts being in the position shown in Fig. 1, whenever the wearing away of the spindle-pintle a or the 50 step f permits the spindle to drop farther into the bolster, and thus increase the friction between the spindle and bolster, the operator, by a suitable tool or device, turns the bolster in a direction opposite to the direction of rotation of the spindle, the inclined surface c⁴ of the teeth c' riding over the pins d until the perpendicular faces c³ of the teeth are reached, when the pins d again act to lock the bolster C and hold it in the position to 55 which it has been turned, and by thus turning the bolster C the pintle F is turned and by means of its threaded connection with the bolster-case is caused to move upwardly, thus raising the step f and removing the excess of 60 friction which was developed by the wear of the parts, as above described.

In the form of the present invention shown

in Fig. 2 the bolster C is suspended at a point near its top or by complementary shoulders c⁶ and d⁶, formed upon the outer surface of the bolster and the inner surface of the bolster-case, respectively. In this form of the present invention the pin d does not support the bolster, but merely acts as a restraining device to restrain the bolster from rotation with the spindle and to hold the parts in their adjusted positions, as before described.

The operation of the construction shown in Fig. 2 to produce an adjustment of the pintle and step is the same as that shown in Fig. 1.

To permit of a slight lateral movement of the bolster under the efforts of the spindle to center itself under an unbalanced load, the parts are loosely fitted to each other, and in the case of a suspended bolster the bearing in the base thereof is preferably slightly flared from a point near the top of said bearing to the bottom thereof, as shown at c⁷, and, if desired, the bolster may be surrounded by 90 any elastic packing or by a film of oil, as usual in these devices.

Having fully described the construction and operation of the present invention, I wish to state that I do not consider the same as limited to the exact details of construction shown and described, but

I claim as new and desire to protect by Letters Patent of the United States—

1. The bolster - case, the bolster placed 100 therein loosely, inclined teeth on the bottom of the bolster, fixed pins engaging said teeth, a vertically-movable pintle carrying the step upon which the spindle rests, mounted in a bearing in the bolster-case, and arranged to 105 be moved vertically in said bearing, substantially as described.

2. The bolster - case, the bolster placed 110 therein loosely, a vertically-movable pintle carrying the step upon which the spindle rests, mounted in a bearing in the bolster-case, and arranged to be moved vertically in 115 said bearing by the rotation of the bolster without manually raising the bolster, substantially as described.

3. The bolster - case, the bolster placed 120 therein loosely, and means for restraining the bolster from rotation, comprising a pin projecting from the bolster - case, and downwardly-extending inclined teeth, on the bolster, substantially as described.

4. The bolster - case, the bolster placed 125 therein loosely, inclined teeth upon the bolster, fixed pins in the bolster-case engaging the teeth on the bolster, arranged to permit 130 a rotation of the bolster in one direction while said bolster maintains a substantially fixed longitudinal position, and to restrain its rotation in the opposite direction and a step arranged to be adjusted by a rotation of the 135 bolster, substantially as described.

5. The bolster - case, the bolster placed 140 therein loosely, means to restrain its rotation in one direction, and to permit its rotation in

the opposite direction and a threaded step mounted in the bolster-case arranged to be adjusted by the rotation of the bolster, substantially as described.

- 5 6. The bolster-case, the bolster placed therein loosely supported at its base, and means to permit a rotation of the bolster in one direction and to restrain it from rotation in the opposite direction, the rotation of the
10 bolster taking place while it remains in a substantially fixed longitudinal position, substantially as described.

7. The bolster-case, the bolster placed

therein loosely, inclined teeth upon the bottom of the bolster, means to engage said teeth 15 to support the bolster, and to permit its rotation in one direction without manually lifting the bolster, and to restrain its rotation in the opposite direction, substantially as described.

20 In testimony whereof I affix my signature in presence of two witnesses.

JOHN KILBURN.
